WORK SUPPORTING TABLE

Charles H. Howland-Shearman, Hamden, Conn.

Application July 27, 1934, Serial No. 737,157

20 Claims. (Cl. 164—86)

This invention relates to work supporting tables for machine tools and devices of a similar nature.

It has for its purpose the provision of a vertically pulsating table applicable to a variety of structure but particularly suitable for use in the Kinetor or tractor lever machine fully set forth in my co-pending application Serial No. 737,160, filed July 27, 1934 and hereinafter described in its relation to the present invention.

10 A further purpose is the provision of means to time the pulsation of the table with respect to the operating functions of the machine.

As a still further object, the invention provides accurate means to control and adjust the amplitude of pulsation of the table and the force applied thereby independently of each other.

Figure 1 is a side elevation of a machine tool embodying the invention.

Figure 2 is a vertical sectional view of the table structure in its lower or retracted position.

Figure 3 is a similar view of the same at the completion of its upward pulsation.

Figure 4 is a transverse section of the table structure.

25 Figure 5 is a fragmental detail view of the means of adjusting the vertical table guide bearings.

Figure 6 is a horizontal sectional view of the vertical wedge and related parts.

30 Figure 7 shows the means of adjusting the initial table position.

Figure 8 is a side view partly in section of the spring motor power storing and tripping means in automatically tripped position.

35 Figure 9 is a vertical cross section of the spring motor and its adjusting means.

Figure 10 is a horizontal cross section of the spring motor cylinder, spring backing nut and adjusting sleeve.

40 Figure 11 is a view similar to Figure 8 but showing the mechanism cocked and at the point of tripping.

Figure 12 is an enlarged detail view of the automatic tripping device showing the shifter block in semi-automatic setting.

Figure 13 is a detail top view of the wedge shown in Figure 12.

Figure 14 is a left side elevation of the same.

Figures 15 and 16 are views of the cushioning dashpot.

Figure 17 is a detail view of a part of the automatic and semi-automatic shifting linkage.

Referring to Figures 1, 2, 3, and 4, the stationary base 11 carries a pair of side plates of which the rear appears in this section and is indicated

by the numeral 12. The plate 12 and its companion plate 13 (Figure 4) are fastened to the base 11 by means of bolts 14 and form therewith the stationary supporting frame of the machine.

The table supporting portion 15 of base 11 is 5 provided with horizontal shoes 16 forming ways for a wedge 17 slideable thereon. A work table 18, guided vertically on stationary rails 19 and 20 in a manner hereinafter described, is provided with lower shoes 21 bearing on the upper inclined surface 22 of the wedge 17. A bolster 23, bolted to the table 18, is adapted to receive die or rest plate which may be of any desired type such as that shown having a main plate 24 and an inserted work portion 25.

It will be noted that bolster 23, table 18, wedge 17 and base 11 are formed with central openings 26, 27, 28, and 29 respectively forming a chamber in the table structure. An ejector rod 30, which may be constructed with a detachable upper portion 31 carrying a shoe 32, is vertically slideable in a stationary sleeve 33 and is adapted to be reciprocated therein by a pedal lever 34 as shown more fully in Figure 4. The purpose of ejector rod 30 is to facilitate the removal of the die or rest plate parts for changes or repairs.

A horizontal rod 35 is fastened in any suitable manner such as the screw thread 36 to the wedge 17. A worm thread 37 is formed on the rod 35 and carries an internally threaded cylindrical member 38 slideable in a stationary guide 39.

A vertical wedge 40 has inclined rear surfaces 41 slideable on a stationary backing guide 42. The guide 42 is formed with side portions 43 and 44, as shown in Figure 6, embracing the sides of an extension 45 of the wedge 40 in dove-tail relation. The wedge 40 is also provided with dove-tail side portions 46 and 47, Figure 6, embracing the sides of a forward shoe 48 which bears in slideable relation against the vertical forward face 49 of wedge 40. The shoe 48 is rotatably retained on a hub 50 of the cylindrical member 38 by a threaded collar 51. A screw key 52 locks the threads of the collar 51 and hub 50.

45 A bevel gear 53 is formed on or fastened to the cylindrical member 38. A second bevel gear 53a, Figure 7, fastened to a shaft 53b journaled in the side plate 13 and having an exterior hand wheel 53c, is adapted to mesh with the gear 53 50 when the latter is in retracted or right hand position.

A toggle arm 54 is articulated to the wedge 40 by means of a pin 55. A lower toggle arm 56, articulated to arm 54 by a pin 57, is fastened at 55

its lower end to a trunnion pin 58 journalled in the base 11.

A link 59 embracing the central pin 57, is pivoted at 60 to the lower lever 61 of a bell crank 62. 5 The bell crank 62 is mounted on a cross shaft 63 secured to the stationary frame of the machine.

The numeral 64 indicates the upper lever of the bell crank 62. Referring to Figure 8, the lever 64 carries a pin 65 which is connected by a short link 66 to a second pin 67 supported in a plunger 68 slideable vertically in a stationary cylinder 69 built integrally with or secured to the base 11.

A nut 70 is adapted to be screwed up or down in the lower threaded portion 71 of cylinder 69. 10 The nut 70 is formed with internal flats 72, Figure 9, slideable longitudinally on corresponding flats 73 on a sleeve 74. A bevel gear 75 is secured to the lower end of the sleeve 74 by means of screw keys 76. A stationary nut 70a retains 15 the sleeve 74 in the cylinder 69. The gear 75 meshes with a second gear 77, Figure 10, mounted on a horizontal shaft 77a extending through the side of the base 11 and carrying an external hand wheel 78. A rod 79, guided in the sleeve 74, 20 is fastened at the top to the plunger 68 and terminates at the bottom in an eye portion 80.

A helical compression spring 81, surrounding the rod 79, is disposed between the piston 68 and a thrust ring 82 carried on the top of sleeve 74. 25 A second compression spring 83 of larger diameter than 81 but shorter length is supported by a thrust bearing 84 on the top of nut 70. A third spring 85, of diameter intermediate springs 81 and 83 but shorter than either is also supported 30 by the thrust bearing 84, which may be of a roller type.

Springs 83 and 85 are preferably wound of wire having a cross section in the shape of a keystone, for reasons hereinafter explained. Disposed between the springs 83 and 85 and the thrust bearing 84 is an indicator plate 86 having a finger 87 extending through a slot 88, Figure 1, in the cylinder 69 and having indicating marks 89 adapted to register with graduation 90 on an external scale 91. A short link 92 connects the eye portion 80 with a walking-beam 93 by means of pins 94 and 95. The walking beam 93 is fulcrumed on a stationary cross shaft 96 supported in the base 11. The right arm 97 of the beam 93 is 40 articulated on pin 98 which is secured in a radius yoke 99. A stationary cross pin 100, suitably secured to the base 11, rotatably supports a beam 101 hereinafter referred to as the micrometer beam, having downwardly extending side walls 102 and 103. The free end of beam 101 comprises a hollow block 104 in which is horizontally trunnioned a sleeve 105 carrying a micrometer screw 106 which is rotatable therein and axially restrained by pinned collars 107 and 108. The 45 screw 106 carries an adjusting hand wheel 106a which projects through the end of the base 11 as shown in Figure 1. An internally threaded nut 109 on screw 106 carries side pins 110 which are journalled in the top of the yoke 99. It will be understood that the yoke 99 spans the walls 102 and 103 of the beam 101.

The pin 98 projects through a curved slot 112 in the base 11, Figure 1, and carries a segmental dial 113 having graduations 114 adapted to register with a stationary pointer 115 when the parts are in the position shown in Figure 8. Rotatably mounted on the side pins 110 are segments 111 slideable in slots 112 in the walls 102 and 103. The 50 slots 112 are cut on a radius struck from the pin 98

when the parts are in the position shown in Figure 8.

A pin 113, located in the longitudinal center of the beam 101, carries a short link 114 which is pivoted by means of a pin 115 to a release plunger 116. The release plunger 116 is vertically slideable in a stationary guide 117. A stop pad 120 of rawhide or other suitable material is provided on the stationary frame 11 under the plunger 116. A lift plunger 121, vertically slideable in the release plunger 116, is secured to a vertical rod 122. The rod 122 is pivotally joined at 123 to an eccentric strap 124 cooperative with an eccentric 125 on a power shaft 126 of the machine. The lift plunger 121 has a lateral notch 127 adapted to receive the end of a latch 128 guided by upper and lower rollers 129 and 130 rotatably mounted in the release plunger 116. A compression spring 131 urges the latch 128 into the notch 127.

A manual release block 132, slidably dovetailed in the top of stationary guide 117, has a plunger 133 urged downward by a spring 134 and adapted to engage a notch 135 in the latch 128. A collar 136 on the top of plunger 133 limits its downward motion. A cross pin 137 in the end of block 132 engages a slot 138 in a lever 139 secured to a cross shaft 140 which is journalled in the side plates 12 and 13 of the machine.

Rockably mounted on a second cross shaft 141, journalled in the base 11, is a lever 142 shown in enlarged scale in Figure 12. The lever 142 contains a slot 143 engaging a pin 144 carried in the enlarged end 145 of a horizontal pull rod 146 fastened to the latch 128. The lever 142 has a laterally extended portion 147 shown in section in Figure 12, and having an inclined inner surface 148 engaging a wedge 149. A key 150, fastened in the extended portion 147 slidably engages a groove 151 in the wedge 149.

A block 152 is slidably dovetailed to the bottom of the wedge 149 as shown in Figure 14. A screw 153, rotatable in a bushing 154 screwed into the bottom of lever 142 and retained therein by a collar 155, is threaded into the block 152 and has an exterior adjusting head 156. By turning the screw 153 the block 152 and wedge 149 may be moved up or down, the dovetail joint between the two permitting the wedge to move left or right as it slides along the inclined inner surface 148 of the lever 142.

A shifter block 157 is slidably dovetailed to the right hand surface or front of the key 149, and is connected through a link 158 and pins 159 and 160 with a short lever 161 fastened to the second cross shaft 141. A second short lever 162, fastened to the shaft 141 behind the parts already described and shown in perspective in Figure 17, carries a pin 163 engaging a slot 164 in a lever 165 rockably mounted on a stationary pin 166. The upper end of lever 165 is connected by a link 167 and pins 168 and 169 with a lever 170 fastened to a rocking shaft 171 journalled in the stationary frame of the machine. A pull rod 172, articulated to lever 170 by pin 119, is pivotally joined to a lever 238 fastened to a shaft 239 as shown in Figure 3. The shaft 239 carries an exterior lever 240 which is connected by a pin 241, a rod 242 and a second pin 243 with a manual positioning lever 176, Figures 3 and 4, fulcrumed on a pin 244 secured to the base 11.

The lever 142, Figure 14, has upper and lower horizontal sideways 182 and 183 between which is slidably disposed a trip block 184 having an extension 185 adapted to engage the shift block 157. The shift block 157 has a cut away portion 186 75

provided to clear the extension 185 when the block 157 is in upper position as shown in Figure 12. The trip block 184 is connected by a short link 187 and pins 188 and 189 with an upward extension 190 of the micrometer beam 101.

Referring to Figure 1, an exterior lever 191 is fastened to the cross shaft 140, and is pivotally connected at 192 to a horizontal link 193 which in turn is pivoted to a spud 194 screwed into a cylinder 195. A piston 196, slideable in cylinder 195, has a reduced piston rod 197 extending slidably through the head 198 of cylinder 195. The rod 197 is threaded into a clevis 199 which is pivoted at 200 to the upwardly extending arm 201 of a bell crank 202 rockably fastened to the base 11 by means of a stationary pin 203. The horizontal arm 204 of the bell crank 202 terminates in a pedal 205.

A pull rod 206, swinging lever 207 and second pull rod 208 connect the upper end of arm 201 with a lever 209 adapted to actuate the trip mechanism (not shown) of a clutch 209a of any suitable type, preferably that shown and fully described in co-pending application Serial No. 737,155, filed July 27, 1934. Retracting springs 210 and 211, connected to the base 11 and side plate 13 respectively, urge the arm 201 and link 193 to the right. A link 212, pivoted at 213 to the micrometer beam 101, is articulated at 214 to a lever 215 rockably mounted on a pin 216 secured in the base 11. The outwardly extending arm 217 of lever 215 is connected by a link 218 to the wrist pin 219 of a piston 220 slideable vertically in a dash pot cylinder 221 secured to the base 11 as shown in Figures 15 and 16.

Vent holes 222 are provided near the top of the cylinder 221, and a longitudinal groove 223 in the bore of 221 leads to a vent port 224 containing a tapered valve 225 having a shank 226 adjustably threaded through a stationary yoke 227. An adjusting handle 228 is provided on the end of shank 226. The numeral 229, Figure 1, indicates a clamping member attached to the working head 230 of the machine. The machine may be actuated by the power shaft 126 through any suitable linkage illustrated by a crank pin 231, connecting rod 232 and lever 233. The shaft 126 may be driven by a motor 234 through a worm 235 and worm gear 236. The numeral 237 indicates a work piece supported by the table 23.

The operation of the device is as follows, assuming the parts to be positioned for automatic tripping as illustrated in Figures 8 and 11. In Figure 8 the springs 81, 83 and 85 have expanded upward, forcing upward the plunger 68 and rocking the bell crank 62 counterclockwise and bringing the toggle levers 54 and 56 to the co-linear position shown in Figure 3. The vertical wedge 40 is thus thrust to its upper position, wedging the shoe 48 and cylindrical member 38 to the left, the member 38 sliding in the guide 39. Member 38 has carried with it the threaded rod 35, which has thrust the wedge 17 to the left and thereby raised the table 18 to its upper position guided by the vertical rails 19 and 20.

The release plunger 116, being connected through the link 114, micrometer beam 101, yoke 99, lever 93 and link 92 with the rod 79 as previously described, is drawn to its lowest position as shown in Figure 8, the pad 120 acting as a stop for 116 and thereby determining the described position of the parts. The eccentric 125 on power shaft 126 having revolved to bottom dead center, Figure 8, the lift plunger 121 had descended inside the release plunger 116 until

the latch 128 has been snapped into the lateral notch 127 by the spring 131. The movement of latch 128, acting through the rod 146, swings the lever 142 clockwise.

The eccentric 125 now revolves past bottom dead center and moves upward, drawing upward the lift plunger 121 which in turn raises the latch 128 and plunger 116, the pin 144 moving upward in the slot 143 of lever 142. As the plunger 116 rises it rocks the beam 101 counterclockwise, raising the yoke 99, rocking the lever 93, drawing the rod 79 and plunger 68 downward. The bell crank 62 is thus swung clockwise, pulling the link 59 to the left and moving the toggle levers 54 and 56 to the angular position shown in Figure 2.

The toggle lever 56 being anchored at 58, the entire vertical or versed sine motion caused by drawing out the toggle acts to draw the vertical wedge 40 downward. The wedge 40, as previously noted, is slidably dovetailed to both the stationary backing guide 42 and the shoe 48. When, therefore, the wedge 40 moves downward it draws the shoe 48, threaded collar 51, cylindrical member 38 and rod 35 to the right, withdrawing the horizontal wedge 17 and allowing the table 18 to move downward by gravity to its lower position as shown in Figure 2.

The downward motion of the plunger 68 compresses the springs 81, 83, and 85, which thereby become a reservoir for stored energy. As the micrometer beam 101 swings clockwise as described, its upper extension 190 moves to the left, sliding the trip block 184 toward the shifter block 157. As the plunger 116 nears the top of its stroke the trip block 184 engages the shifter block and moves the latter to the left, causing the lever 142 to swing also to the left. The pin 144 and rod 146 are pulled to the left, withdrawing the latch 128 from the lateral notch 127 as shown in Figure 11. The entire linkage compressing the springs 81, 83, and 85 is thereby freed from the lift plunger 121. The springs immediately expand, suddenly returning the parts to the positions shown in Figures 3 and 8, except the eccentric 125, lift plunger 122 and their interconnections. The table 18 is thus given a rapid pulsation upward, the release plunger 116 dropping simultaneously. The incidental downward swing of the micrometer beam 101 is communicated through the link 212 to the lever 215, rocking the outer arm of 215 upward and thereby raising the dash-pot piston 220, Figures 15 and 16. The air trapped in the dash-pot cylinder 221 above the piston 220 is forced out through the small holes 222 and the port 224, the resistance to its exit giving a cushioning effect as the release plunger 116 approaches the stop pad 120. The degree of cushioning effect may be varied by adjusting the restriction of port 224 by means of the tapered valve 225.

From the foregoing description it is evident that the complete pulsating cycle of the table consists of a relatively slow downward or retracting movement followed by a sudden upward movement. Due to the long stroke of the spring actuated plunger 68 and the compounded speed reduction of the toggle levers 54 and 56 and the wedges 40 and 17, the total rise of the table is relatively small. The effective force of the powerful springs 81, 83 and 85 is therefore multiplied many times and notwithstanding the inertia of the parts the upward stroke of the table is practically instantaneous, subject only to the adjustable cushioning effect of the dash-pot 221.

The entire pulsating cycle occurs during one half revolution of the power shaft 126, that is during the upward travel of the plunger 121, the tripping of the latch 128 occurring near the top 5 of the stroke. The timing of the pulsating cycle with respect to the working function of the machine tool is determined by the set position of the eccentric 125 on the shaft 126. With machines such as the Kinetor, having one working and one 10 idling or retracting stroke, Figure 1, the eccentric 125 is generally set to reach top dead center at the commencement of the working stroke.

The timing of the withdrawal of latch 128 from the notch 127 in relation to the stroke of the 15 plunger 121 and consequently to the working function of the machine is determined by the engagement of the trip block 184 with the shifter block 157 as previously described. By means of the screw 153, Figure 12, the wedge 149 may be 20 adjusted upward or downward, thus moving the shifter block 157 to the right or left, causing an earlier or later engagement between the blocks 184 and 157. By this means an accurate and delicate adjustment of the tripping and consequent upward table pulsation is provided.

To vary the amplitude of the table pulsation, the machine is stopped with the parts in the position shown in Figure 8. If it is desired to shorten the stroke, the micrometer screw 106 is operated by means of the hand wheel 106a, Figure 1, to move the nut 111 to the left. The slots 112 being cut on a radius swing about the center of the pin 98 in the position shown in Figure 8, the position of 98 is not altered, but the segments 30 109 and pins 110 are moved near the fulcrum 100 of the beam 101. Consequently, when the beam 101 is raised by the action of the lift plunger 121, the link 99 imparts a shorter motion to the lever 97. By this means the table is given a shorter 40 stroke without alteration in its upper position.

Similarly, by moving the nut 111 to the right the stroke may be lengthened.

The external dial 173, which registers with the pointer 175, Figure 1, when the parts are as 45 shown in Figure 8, swings with the link 99. The graduations 174 are calibrated as increments of table movement. Consequently the table stroke and adjustments thereof may be read directly on the external dial 173. As the adjustment takes 50 place at a point in the linkage where the movement of the parts is very large in relation to the corresponding table movement, the setting of the latter is rendered very fine and accurate.

The position of the table 18 may be adjusted as 55 follows:

With the table in retracted position, as shown in Figure 2, the bevel gear 53 is adapted to mesh with the second bevel gear 53a when the latter is moved inward manually as shown in Figure 7. 60 By turning the hand wheel 53c the member 38 is revolved on the thread 37 thus moving the rod 35 longitudinally. The wedge 17 is thus shifted to lower or raise the table 18. A spring 245 is provided to slide the shaft 53b outward and 65 thereby hold the gear 53a out of meshing position with gear 53 except when the wheel 53c is pressed inward to make an adjustment.

To increase the force delivered by the springs 81, 83 and 85, and consequently the upward force 70 imparted to the table and work material above it, the hand wheel 78, Figure 9, is revolved, causing the gear 77 to revolve the mating gear 75 and with it the sleeve 74. The nut 70, being rotatively locked to sleeve 74 by the flats 72 and 73, 75 Figure 10, is screwed upward in the threads 71 of

cylinder 69, thus compressing the springs 81, 83, and 85 against the plunger 68. The initial compression thus being increased, the springs after further compression by the lowering of the plunger 68 are adapted to raise the table 12 with increased force when the release apparatus is tripped.

Figure 9 shows the nut 70 in its lowest position. As previously noted, the springs 81, 83 and 85 may have different free lengths, so that with the nut at lowest position only the spring 81 10 normally bears against the plunger 68, the other springs being picked up successively as the nut is adjusted upward. This arrangement allows a greater range of adjustments than could be obtained if all springs were employed throughout 15 the entire range.

The scale 91 is calibrated to read directly in upward force exerted through the table by a given combination and setting of springs.

The use of "keystone" wire in springs 83 and 85 promotes uniformity of graduation on the scale 91, as this type of spring when compressed gives an increase in pressure directly proportional to the linear decrease in length.

The operation of the device as thus far described has dealt with fully automatic action of the machine tool, the shaft 126 revolving continuously. With some classes of work it may be necessary to operate the machine intermittently, as for instance when work must be placed on the 30 table and located by hand. For this purpose manual means of tripping the pulsating apparatus is employed as follows:

The positioning lever 176 is moved to the right, Figure 3, acting through the rod 242, levers 240 35 and 238 to swing the lever 170 Figures 8, 11, and 17, counterclockwise. The lever 170, through the link 167 swings the lever 165 clockwise, causing the slot 164 to impart a counterclockwise motion to the pin 163, short lever 162, shaft 141, 40 and lever 161, Figure 12. The motion of 161 is transmitted through the link 158 to the shifter block 157 which is moved upward to the position shown in Figure 12.

When the trip block 184 is now moved to the 45 left by the upward motion of beam 101, the extension 185, instead of encountering the shifter block 157, enters the clearance cut-out or notch 186 and hence does not trip the latch 128.

Assuming the machine to have been stopped 50 by disengagement of the clutch 209a with the working parts about to start the work stroke, that is with the eccentric 125 at or near top dead center, the spring motor has been cocked by the preceding rise of the lift plunger 121 as previously described and is held cocked by the latch 128. The plunger 133 of the manual release block 132 has engaged the notch 135 in the latch 128. The loading or positioning of the work having been completed, to trip the table pulsating mechanism 60 the pedal 205 is depressed as shown in Figure 1. The lever 202 swings to the left, acting through the rod 197, piston 196, cylinder 195, spud 194 and link 193 to rock the lever 191, shaft 140 and lever 139 clockwise. The lever 139 draws the 65 block 132 to the left and the plunger 132 in notch 135 withdraws the latch 128 from the notch 127 to trip the spring motor. The table performs its upward pulsation. At the same time the lever 201, Figure 1, may act through the rod 206, lever 70 207, rod 208 and lever 209 to trip the clutch 209a, thus starting the machine on its working stroke.

The device cannot be tripped manually unless the eccentric 125 is in proper position and the spring motor cocked, as the plunger 133 can 75

engage the notch 135 in the latch 128 only when the release plunger 116 is at or near the top of its stroke.

To illustrate a use of the functions of the pulsating table, it may be assumed that a work piece 237 is to be pressed upward against the clamping member 229 of the Kinetor, Figure 1, with a force previously determined as required by the work to be done on the material. It having also been determined from the nature of the material, possible thickness of scale or surface irregularities, and initial clearance between the work and clamping member 229, that a certain upward motion of the table is required to give proper clamping, the length of upward pulsation is set by means of the micrometer screw 106 and dial 173. The spring motor is next adjusted to give the desired force as previously described by means of hand wheel 78.

The work piece having been placed in position, the device is tripped. The table pulsates upward pressing the work firmly between the rest plate 24-25, Figure 2, and the clamping member 229 and holding it thus while the required work is performed on it. The machine tool having performed its work, the table 18 is lowered as previously described, allowing the work piece 237 to be removed and replaced by a new piece.

The wide independent adjustments of the pressure and amplitude of pulsation allow the device to be set for a wide range of work, both heavy and light, and the fineness of the adjustments make it suitable for use where extreme delicacy and accuracy are required. In some cases it may be desired to bring the work to full clamped condition before the toggle levers 54 and 56 are entirely aligned, which purpose may be accomplished by a slight increase of the setting for amplitude.

The low angles of the wedges 17 and 40, together with the fact that the toggle 56-54 when at or near alignment approximate a rigid column, prevent any downward yielding of the table 18 under working pressure which may be applied to the piece 237.

The forward pulsation of the heavy wedge 17 against the lower incline face of the table 18, especially when large pulsating forces are being employed, imparts a horizontal component or throb to the table 18. These horizontal pressure pulsations are resisted by the vertical guide rails 19 and 20, and in time wear will result. To take up this wear and prevent looseness and loss of proper alignment the table 18 is equipped with wedge-shaped shoes 246 and 247, Figure 5, engaging each rail. A yoke 248 spanning the rail 20 is adjustable upward and downward by means of nuts 249 and 250 on a stud 251 fastened in the table 18. Similar studs 252 and 253 passing through slotted holes 254 and 255, adjustably secure the shoes 246 and 247 to the ends of the yoke 248. The shoes are backed by inclined plates 256 and 257 secured to the table 18.

By setting the yoke 248 upward on the stud 251 both wedges may be roughly adjusted, while individual adjustment of the shoes may be made to give accurate clearance and alignment.

From the foregoing description it is evident to those skilled in the art, that the invention involves a result hitherto unobtained, namely, a quick table pulsation of separately adjustable predetermined amplitude and force, differing both in nature and function from the ordinary working, feeding or locating movements em-

ployed on planers, milling machines and similar tools.

While the invention is presented in preferred form as reduced to practice, it is not limited to the exact structure shown, as various modifications can be made without departing from the scope of the appended claims.

What is claimed is:

1. In combination working pressure applying means, a machine table having a work supporting face, means to pulsate said table perpendicularly to said face, to apply a predetermined pressure to a material supported on said table previous to the operation of said working pressure applying means, and means for holding said table in fixed position to permit said pressure applying means to perform work on said material. 10

15 2. In a machine tool in combination working pressure applying means, a power shaft, a horizontal work supporting table, means controllable by said power shaft to pulsate said table vertically, to apply a predetermined pressure to a material supported on said table previous to the operation of said working pressure applying means, and means for holding said table in fixed 20 position to permit said pressure applying means to perform work on said material. 25

3. In a machine tool in combination a power shaft, a work supporting table, and means to pulsate said table comprising means operable by said shaft to store energy, means operable by said shaft to release said energy, and means to operatively apply said energy to said table. 30

4. In a machine tool in combination a power shaft, a work supporting table, and means to pulsate said table comprising means operable by said shaft to store energy, means operable by said shaft to release said energy in timed relation to the operation of said storing means, and means to operatively apply said energy to said 40 table. 35

5. In a machine tool in combination a power shaft, a work supporting table, and means to pulsate said table comprising means operable by said shaft to store energy, manually operable 45 means to release said energy, and means to operatively apply said energy to said table.

6. In a machine tool in combination a power shaft, a work supporting table, and means to pulsate said table comprising means operable by said shaft to store energy, means operable by said shaft to release said energy, manually operable means to release said energy, and means to operatively apply said energy to said table. 50

7. In a machine tool in combination a power shaft, a work supporting table, and means to pulsate said table comprising means operable by said shaft to store energy, means operable by said shaft to release said energy in adjustably timed relation to the operation of said storing means, and means to operatively apply said energy to said table. 55

8. In a machine tool in combination, a work supporting table, means to apply to and withdraw from said table a predetermined force to cause a pulsation thereof, manually operable means to vary said predetermined force, and manually operable means to vary the amplitude of said pulsation. 60

9. In a machine tool in combination, a work supporting table, means to apply to and withdraw from said table a predetermined force to cause a pulsation thereof, manually operable means to vary said predetermined force, and manually operable means to vary the amplitude of said 70

75

first manually operable means, to vary the amplitude of said pulsation.

10. In a machine tool in combination, a work supporting table, means to apply to and withdraw from said table a predetermined force to cause a pulsation thereof, manually operable means to vary said predetermined force, and manually operable means, including a micrometer screw, to vary the amplitude of said pulsation. 5

11. In a machine tool in combination, a work supporting table, means to apply to and withdraw from said table a predetermined force to cause a pulsation thereof, manually operable means to vary said predetermined force, manually operable means independent of said first manually operable means, to vary the amplitude of said pulsation, and manually operable means to adjust the position of said table. 10

12. In a machine tool in combination, a work supporting table, means including a toggle to apply to and withdraw from said table a predetermined force to cause a pulsation thereof, manually operable means to vary said predetermined force, and manually operable means to vary the amplitude of said pulsation. 15

13. In a work supporting and clamping device, in combination, a base, a table slidably guided thereby, wedging means adapted to move said table, second wedging means adapted to actuate said first wedging means, a toggle operatively attached to said second wedging means, and power means to actuate said toggle. 20

14. In a work supporting and clamping device, in combination, a base, a table slidably guided thereby, wedging means adapted to move said table, second wedging means adapted to actuate said first wedging means, a toggle operatively attached to said second wedging means, and power means to actuate said toggle through a predetermined amplitude. 25

15. In a work supporting and clamping device, in combination, a base, a table slidably guided thereby, wedging means adapted to move said table, second wedging means adapted to actuate said first wedging means, a toggle operatively attached to said second wedging means, power means to actuate said toggle through a predetermined amplitude. 30

16. In a work supporting and clamping device, in combination, a base, a table slidably guided thereby, wedging means adapted to move said table, second wedging means adapted to actuate said first wedging means, a toggle operatively attached to said second wedging means, and power means to actuate said toggle through a predetermined amplitude with a predetermined force. 35

17. In a work supporting and clamping device, in combination, a base, a table slidably guided thereby, wedging means adapted to move said table, second wedging means adapted to actuate said first wedging means, a toggle operatively attached to said second wedging means, power means to actuate said toggle through a predetermined amplitude with a predetermined force, manual means to vary said predetermined force and manual means to vary said amplitude. 40

18. In a work supporting and clamping device in combination, a base, guide rails thereon, a table, guide shoes attached to said table, and slidably engaging said rails and wedging means to pulsate said table, said shoes being adjustable to take up wear between said shoes and said rails. 45

19. In a machine tool in combination a power shaft, a work supporting table, and means to pulsate said table comprising means operable by said shaft to store energy, tripping means operable by said shaft to release said energy in timed relation to the operation of said storing means, and means to operatively apply said energy to said table. 50

20. In a work supporting and clamping device, in combination, a base, a table slidably guided thereby, wedging means adapted to move said table, a second wedging means adapted to actuate said first wedging means, a toggle operatively attached to said second wedging means, power means to actuate said toggle in one direction and to store a predetermined quantity of resilient energy, and means to release said energy to actuate said toggle in the other direction. 55
